UNITED STATES PATENT OFFICE.

JOSIAH J. DEAL, OF CANTON, OHIO, ASSIGNOR TO THE DAYTON KEYLESS LOCK COMPANY,
OF DAYTON, OHIO, A CORPORATION OF OHIO.

COMBINATION-LOCK.

No. 925,688.

Specification of Letters Patent. Patented June 22, 1909.

Application filed August 5, 1907. Serial No. 387,053.

To all whom it may concern:

Be it known that I, JOSIAH J. DEAL, a citizen of the United States, residing at Canton, in the county of Stark and State of Ohio, 5 have invented certain new and useful Improvements in Combination-Locks; and I do hereby declare that the following is a full, clear, and exact description of the same, reference being had to the accompanying drawings, making a part of this specification, and to the numerals of reference marked thereon, in which—

Figure 1 is a view showing the lock open and the locking lever set and locked. Fig. 2 15 is a view showing the different parts and the locking lever released. Fig. 3 is a view showing the different parts in their positions when the combination has been worked, and the knob spindle released and free to turn. Fig. 4 is a view showing the locking lever in 20 position to be moved by the knob spindle. Fig. 5 is a detached view of the locking dog. Fig. 6 is a detached view of one of the disk operating bars, its disengaging finger and 25 spring. Fig. 7 is a detached view of the inner knob spindle. Fig. 8 is a view showing the outer knob spindle, its locking disk, the locking lever and the locking lever knob and its spring. Fig. 9 is a view showing the 30 lock open and the knob spindle free to turn and the locking lever set back and free to turn. Fig. 10 is an edge view of the lock showing the casing in section. Fig. 11 is a view similar to Fig. 9, except the knob spindle is locked against rotation. Fig. 12 is a 35 view showing the lock proper applied to an ordinary and common lock. Fig. 13 is a view of the locking lever setting knob or spindle. Fig. 14 is a view showing a portion of the lock casing showing the different spacing disks and a setting disk and also showing the locking disk detached.

The present invention has relation to combination locks and it consists in the different 45 parts and combination of parts hereinafter described and particularly pointed out in the claims.

Similar numerals of reference indicate corresponding parts in all the figures of the 50 drawing.

In the accompanying drawings, 1 represents the case, which may be of the form shown and is formed of such a size that the different parts intended to be located therein

can be properly arranged and connected. 55 The case 1 is secured to the ordinary lock case 2 or to a door as the case may be by means of suitable connecting bolts 3 or their equivalents. The outer knob spindle 4 is provided with the usual knob 5. To the 60 outer knob spindle 4 is securely attached or formed integral therewith the spindle head 6, which is provided with the screw threaded aperture 7 into which screw threaded aperture is seated the screw threaded end 8 of 65 the inner knob spindle 9. The spindle head 6 is provided with the lateral lug 10, which lateral lug is for the purpose of limiting the movement of the inner knob spindle 9 by reason of the pin 11 coming in contact 70 with said lug, thereby allowing the inner knob spindle to be rotated at any time and the lug 10 is also for the purpose of coming in contact with the pin 11 so that when the outer knob spindle is rotated the inner knob 75 spindle will be rotated with it.

The case 1 is provided with the hollow post 12 upon which post are located any desired number of spacing disks 13, toothed disks 14, lock disks 15, said disks being varied as to number reference being had to the number of locking disks designed to be employed. In the present case three lock disks are employed but of course the number may be increased or decreased without changing 80 the nature of the invention but two lock disks must be employed to bring about a true combination. The spacing disks 13 are provided with the extensions 16, which extensions are notched for the purpose of receiving the pin 17, which pin is fixed to the case 1. The toothed disks 14 are provided with the pins 17^a which pins are for the purpose of connecting the lock disks 15 by means of the apertures 18, the combination 90 being changed from time to time by placing the pins 17^a in different apertures formed in the lock disks 15.

For the purpose of setting the locking disks the toothed disks are provided with the 100 extensions 19, which extensions are so located that when the setting disk 20 is rotated the pin 21 will engage the extensions 19 and thereby set the lock disks so that the predetermined combination can be counted 105 and the knob spindle released. The lock disks are each provided with the notches 22, which notches can be brought into proper

alinement with the notches 23 formed in the spacing disks 13 and the notch 24 formed in the setting disk 20. The dog 25 is free to be carried downward by means of the 5 spring 26, which spring is located through the aperture 26^a formed in the right angled portion of the dog 25 and when carried downward it releases the spindle head 6 together with the knob spindles 4 and 9.

- 10 For the purpose of providing a means for actuating the setting disk 20 the setting knob 27 is provided, which setting knob is provided with the spindle 28, which spindle is provided with the angled end 29, which 15 angled end is secured to the setting disk 20 by means of the screw 30 and the angled aperture 31.

The dog 25 is pivotally attached to the case 1 and is located substantially as shown 20 in the drawings and the spring 26 is connected to the screw 32, which pivotally connects the dog 25 to the case. The dog 25 is provided with the lateral lug 33 through which lug the spring 26 is extended and said 25 spring so tensioned that it will have a tendency to move the dog down when free as above described.

The spindle head 6 is provided with the stop 34, which stop is for the purpose of 30 preventing rotation of said spindle head 6 and the lock spindles 4 and 9.

To the casing 1 is attached or formed integral therewith the lug or boss 35, upon which lug or boss is movably mounted the 35 locking lever 36, which locking lever is provided with the hook 37, which hook is located below the lateral lug 33 formed upon the dog 25, said hook being for the purpose of engaging said lateral lug for the purpose 40 hereinafter described.

The spindle head 6 is provided with the cam lug 38, which cam lug is for the purpose of engaging the pin 39, which pin is connected to the locking lever 36. It will 45 be understood that when the locking lever is located as shown in Figs. 9 and 11 the cam lug 38 will not come in contact with the pin 39, but will pass said pin without coming in contact therewith; but when the locking 50 lever is brought into the position shown in Figs. 1, 2 and 3 the cam lug 38 will engage the pin 39 and move the locking lever 36 downward as illustrated in Fig. 4, and when the hook 37 has come fully under the lug 33 55 the spring 40 will move the locking lever up carrying with it the dog 25; but this movement cannot take place until the shoulder 34 has been carried out of the way of the dog and in order to automatically do this the 60 spring 41 is provided, which spring forces the spindle head 6 into the position shown in Fig. 1.

For the purpose of limiting the back action of the spindle head 6, the pin 42 is pro-

vided, which pin is so located that the cam 65 lug 38 will come in contact with said pin, and stop the backward movement of the spindle head 6.

For the purpose of actuating the lock for a given combination, the movable bars 43 70 are provided and are located side by side as best illustrated in Fig. 10, their upper ends being held by the guide 44, which guide is connected to the lock casing 1 in any convenient and well known manner. To the 75 operating bars 43 are pivotally attached the fingers 45, which fingers are for the purpose of engaging the teeth upon the toothed disks 14.

For the purpose of causing the fingers 45 80 to properly engage the teeth of the toothed disks 14, the springs 46 are provided, which springs are connected to the bars 43 and press against the shoulders 47. When it is desired to bring the locking lever 36 out of 85 action the knob 48 is moved upward as illustrated in Figs. 9 and 11, but when it is desired to bring the locking lever into action the knob 48 is pushed down, which knob carries the cam plate 49, which cam plate 90 comes in contact with the locking lever 36, and moves its lower end so as to bring the same into proper position to be actuated by the cam lug 38 and the pin 39.

For the purpose of automatically lowering the operating bars 43 the springs 50 are provided the ends of which springs are located in the notches 51 formed in the bottom or lower ends of the bars 43. It will be understood that the bars 43 should be 100 provided with operating knobs 52, which knobs extend through the casing 1.

For the purpose of moving the locking lever back after it has been moved by the knob 48 the setting disk 20 is provided with 105 the pin 53 which pin comes in contact with the bottom or lower end of the lever and moves the lever into the position shown in Fig. 2.

Having fully described my invention 110 what I claim as new and desire to secure by Letters Patent, is—

1. In a combination lock, a casing, an outer knob spindle and an inner knob spindle rotatable independent of each other, the 115 outer knob spindle provided with a spindle head, said head provided with a cam lug, a locking lever provided with a pin adapted for engagement with the cam lug upon the spindle head, said locking lever also provided with a hook at its bottom or lower end, a dog adapted to engage the bottom or lower end of the locking lever, a post having mounted thereon, a series of toothed disks, spacing disks and locking disks, said toothed 120 disks having extensions formed thereon, a spindle mounted in said post, a setting disk secured to said spindle, said setting disk

provided with a pin and means for holding the spacing disks against rotation, substantially as and for the purpose specified.

2. In a combination lock, a case, knob spindles rotatable independent of each other, a spindle head provided with a stop and a cam lug, a lever provided with a hooked extension, a dog adapted to engage the stop of the spindle head when elevated, a pin carried by the lever and springs adapted to elevate the lever and dog, substantially as and for the purpose specified.

3. In a combination lock, a case, knob spindles rotatable independent of each other, a spindle head provided with a stop and a cam lug, a lever provided with a hooked extension, a dog adapted to engage the stop of the spindle head when elevated, a pin carried by the lever, springs adapted to elevate the lever and dog, a series of locking disks, toothed disks, and spaced disks, and means for actuating the toothed disks, substantially as and for the purpose specified.

4. In a lock of the character described, a case, outer and inner spindles, one of the spindles provided with a head, said head provided with a stop, a dog located below the head, a lever pivotally connected to the casing and provided with a hooked lower end, means carried by the head and lever whereby the lever is actuated by the movement of the spindle head and means for elevating the lever, substantially as and for the purpose specified.

5. In a lock of the character described, a case, outer and inner spindles, one of the spindles provided with a head, said head provided with a stop, a dog located below the head, a lever pivotally connected to the casing and provided with a hooked lower end, means carried by the head and lever, whereby the lever is actuated by the movement of the head, a spring for elevating the head and a series of toothed and locking disks and a setting disk, substantially as and for the purpose specified.

6. In a lock of the character described, a case, knob spindles, a spindle head mounted upon one of the knob spindles, said spindle head provided with a stop, a dog adapted to engage the stop of the spindle head, a spring connected to the dog, a locking lever pivotally and slidably mounted in the casing and a spring connected to the locking lever, said locking lever provided with a hooked lower end adapted to engage the dog, a series of spacing locking and toothed disks mounted below the dog, said locking disks provided with notches, a setting disk provided with a notch, the dog adapted to engage the notches of the disks, said toothed disks provided with extensions, a pin carried by the setting disk adapted to engage the extensions of the toothed disks and a setting spin-

dle, substantially as and for the purpose 65 specified.

7. In a lock of the class described, the combination of a casing with knob spindles, a spindle head carried by one of the knob spindles, said spindle head provided with a stop, a dog located below the spindle head and adapted for engagement with the stop, a lever extended downward and below the spindle head, a setting disk mounted upon a setting spindle, said setting disk provided 75 with a pin adapted for engagement with the bottom or lower end of the lever and a spring adapted to elevate the lever when released, substantially as and for the purpose specified.

8. In a lock of the class described, the combination of a casing with knob spindles, a spindle head carried by one of the knob spindles, said spindle head provided with a stop, a dog located below the spindle head 85 and adapted for engagement with the stop, a locking lever extended downward and below the spindle head, a setting disk mounted upon a setting spindle, said setting disk provided with a pin adapted for engagement 90 with the bottom or lower end of the locking lever, a spring adapted to elevate the locking lever when released, a series of notched locking disks, toothed disks provided with extensions, and a setting disk provided with 95 a pin adapted for engagement with said extensions, substantially as and for the purpose specified.

9. In a combination lock, a series of combination disks having each a peripheral 100 notch and a series of openings concentric to its axis, a corresponding number of interlocking actuating disks, each of which is provided with ratchets on its periphery and a pin concentric to the axis thereof and 105 adapted to interlock with one of the openings in the adjacent combination disk, each of said interlocking-actuating disks being provided with a peripheral extension in a plane with the disk, a zero-setting disk having a peripheral arm extending at right angles to the plane of the disk and adapted to engage the peripheral extensions on the interlocking-actuating disks to move said interlocking disks and the combination disks 115 to their zero or initial positions, a stationary pin or abutment limiting the movements of the interlocking-actuating disks when being set to their initial positions, a spring-controlled dog having a downwardly-extended 120 portion adapted to enter the peripheral recesses in the combination disks, a spindle head having a stop thereon, a portion of the dog, adapted to engage the stop on the spindle head to lock the spindle when the projecting end of the dog engages the peripheries of the combination disks, a spring engaging a shoulder upon the spindle head 125

to maintain the head in a position with the stop thereon in alignment with the projected end of the dog, and a depending lever, the lower end of which is adapted to maintain 5 the dog from engagement with the combination disks at predetermined times.

10. In a combination lock, an outer knob spindle, a head thereon having a stop and stop lugs, a pin engaging the stop lugs to 10 limit the oppositely-rotatable movements of said head, a spring-pressed dog having an end bent at right angles and extending on one side of the plane of said dog, a spindle in a plane below the outer knob spindle and 15 inclosed within a hollow bearing, a series of combination disks and their interlocking-actuating disks mounted upon said hollow bearing concentric with the spindle within said bearing, each of the combination disks 20 having a recess in its periphery adapted to receive the lower portion of the end of the dog, a depending lever adapted to hold the dog from engagement with the combination disks at predetermined times, each of the 25 interlocking-actuating disks having a peripheral extension, a setting disk rotatable with the spindle, said setting disk being provided with an arm lying at a right angle to the plane of the disk and adapted to engage 30 the peripheral extensions on the interlocking-actuating disks to set said disks and therewith the combination disks to their initial positions, means for actuating the interlocking disks to bring the peripheral recesses 35 therein in alignment with the end of the dog, and a stationary pin or abutment engaging the peripheral extensions on the interlocking actuating disks to limit their resetting movements.
40. 11. In a combination lock, an outer knob spindle, a spindle head connected with said knob spindle, said head having a stop thereon, a spindle located below the spindle head in a hollow bearing, a series of combination 45 disks and interlocking-actuating disks adapted to be interlocked at different points, means for changing the points of connection between the said disks consisting of pins adapted to interlock in openings in the adjacent 50 combination disk, means for actuating the interlocking actuating disks, a spring-pressed dog interposed between the spindle head and the combination disks, said dog having an end bent at right angles and on 55 one side of the plane of the dog, said bent end being adapted to engage the stop on the spindle head or the notches in the combination disks when said notches are brought into alignment therewith, a depending lever 60 adapted to hold the dog from engagement with the combination disks at predetermined times, a setting disk secured to the spindle and having a peripheral arm lying at a right angle to the plane of the disk, the interlocking-actuating disks having peripheral exten-

sions adapted to be engaged by the peripheral arm on the setting disk whereby said actuating disks and therewith the combination disks are moved to zero, and a stationary abutment limiting the setting movements of 70 the interlocking-actuating disks.

12. In a combination lock, an outer knob spindle, a head on said spindle having a stop thereon and a cam surface, a series of combination disks and their interlocking-actuating disks assembled upon a common axis of rotation, said combination disks having each a stop thereon, an individual actuating bar co-operating with each of the actuating disks of the combination disks, a spring-pressed 80 dog having an end terminating at right angles to the plane of said dog, the lower portion of said right angled end being recessed and adapted to enter the notches in the combination disks while the upper portion of said 85 end is adapted to engage the stop on the spindle head, a depending lever having a hook on its lower end adapted to move across the recessed portion of the dog to hold the same from engagement with the combination 90 disks, said lever having a pin thereon engaged by the cam on the spindle head whereby the lever is moved to such position, and means for giving the lever its initial movement from its normal position.

13. In a combination lock, an outer knob spindle, a head on said spindle having a stop, a series of combination disks with their interlocking-actuating disks, each combination disk having a peripheral recess and each interlocking-actuating disk having a peripheral extension, means for interlocking each combination disk with its companion-actuating disk at predetermined points, means for actuating each of the interlocking disks 105 through which the combination disks are operated to bring their peripheral recesses in alignment, a spring-controlled dog having an end turned at a right angle on one side of the plane of the dog, said end being 110 adapted to engage the stop on the spindle head or the recesses in the combination disks, a depending lever adapted to hold the dog from engagement with the combination disks at predetermined times, means engaging the peripheral extensions of the interlocking actuating disks to move them to their initial positions and therewith the combination disks, and a stationary abutment stopping the movement of said disks at such position.

14. In a combination lock, an outer spindle and knob, a head on said spindle, said head having a stop on its lower periphery and stops projecting from its upper periphery, a stationary stop pin located between 125 said last named stops, a series of interlocking-actuating disks, a series of combination disks, means for interlocking said disks at predetermined points in selecting a combination, said combination disks having each a 130

- peripheral recess, means engaging the interlocking and actuating disks to move the combination disks to bring the peripheral recesses thereon in alinement, a spring-controlled dog having its end bent at a right angle, said end having its lower portion recessed and adapted to enter the alined recesses in the combination disks, and the upper portion of said end being adapted to engage the stop on the lower periphery of the spindle head, a depending lever adapted to be moved to a position to hold the end of the dog out of engagement with the combination disks, means for moving said lever to such position when turning the outer knob spindle and therewith the spindle head after the latter has been released by the end of the dog, and means for giving said depending lever its first or initial movement.
- 15 13. In a combination lock, an outer knob spindle, a head on said spindle having a stop thereon, an extension from said head, a leaf spring engaging said extension to hold the head normally in position with the stop thereon in a vertical position below the axis of the head, stops projecting from the upper portion of said head, a stationary abutment on the lock casing engaging said stops to limit the opposite movements of the head, a cam on said head, a series of combination disks and their interlocking actuating disks mounted upon a spindle below the knob spindle, means for changing the relative positions of each interlocking disk and its companion disk, the combination disks having each a peripheral recess, means for actuating each interlocked set of disks to bring the recesses in alinement, a spring-controlled dog interposed between the spindle head and the disks, said dog having its end bent at a right angle and the upper portion thereof being adapted to interlock with the stop on the spindle head, the lower portion of said dog end being recessed to provide a shoulder on the upper portion of said end, a depending lever having its lower end adapted
- 20 to engage said shoulder to hold the dog in an elevated position, said lever having a lower extended portion, a pin extending from the inner side of said lever and engaged by the cam on the spindle head and whereby said lever is moved to the position to maintain the dog in said elevated position, a sliding cam adapted to initially move said lever, and means for setting the disks to their initial positions and for moving the lever from the position engaging the dog, said means comprising a setting disk having a peripheral extension lying at a right angle to the plane of the disk and adapted to engage peripheral extensions on the interlocking-actuating disks, and said setting disk having a projection adapted to engage the lower extended portion of the depending lever and to move said lever out of engagement with the end of the dog.
- 25 16. In a combination lock, a spindle head having a stop thereon, a series of combination disks having recesses therein, means for actuating said disks to bring the recesses in alinement, a spring-controlled dog having its end bent and the upper portion thereof being adapted to interlock with the stop on the spindle head, a shoulder formed on said end, and the lower portion of said end being adapted to enter the recesses in the combination disks, a depending lever having an engaging end adapted to maintain the dog in an elevated position by engaging the shoulder on the end of said dog, means for moving said lever to such position, means for moving it from such position, means for actuating the combination disks, and means for setting them in their initial positions.
- 30 In testimony that I claim the above, I have hereunto subscribed my name in the presence of two witnesses.
